UNITED STATES PATENT OFFICE.

VICTOR M. SUMMA, OF ST. LOUIS, MISSOURI.

DUMP-CAR.

No. 849,175.

Specification of Letters Patent.

Patented April 2, 1907.

Application filed March 20, 1906. Serial No. 307,055.

To all whom it may concern.

Be it known that I, VICTOR M. SUMMA, a citizen of the United States, residing at St. Louis city and State of Missouri, have invented new and useful Improvements in Dump-Cars, of which the following is a specification.

This invention relates to dump-cars, and is in the nature of an improvement upon the construction disclosed in my former patent, No. 755,412, granted March 22, 1904, the object of the present invention being to simplify and improve the construction disclosed in said patent and to facilitate the adjustment of the parts of the mechanism and facilitate the transformation of the car from an ordinary flat gondola into either a center-dump or side-dump car, and vice versa.

With the above and other objects in view, the nature of which will more fully appear as the description proceeds, the invention consists in the novel construction, combination, and arrangement of parts hereinafter more fully described, illustrated, and claimed.

In the accompanying drawings, Figure 1 is an end view of a dump-car embodying the present invention. Fig. 2 is a vertical longitudinal section through the same. Fig. 3 is a cross-section through the car, showing in full lines the several doors or sections thereof set to form a flat-car and showing in dotted lines the position the center doors assume to form a side-dump car. Fig. 4 is a section similar to Fig. 3, showing the several doors or sections adjusted to constitute a center-dump car. Fig. 5 is a detail cross-section through one of the side stakes or vertical braces in line with the longitudinal stiffener. Fig. 6 is a detail vertical section showing a modified connection between the side sills and cross-sills. Fig. 7 is a detail section on the line 7 7 of Fig. 6.

The car in its general construction embodies the end cross-sills 1 and a series of intermediate cross-sills or diaphragms 2, which are all connected by center sills 3, extending longitudinally of the car and beneath the plane of the bottom thereof. The car also comprises the side girders 4 and the ends 5, which form the box or body of the car.

The floor of the car is composed of several sections or doors, 6 and 7 designating the center doors, and 8 the lower sections of the side doors, while 9 designates the upper sections of the side doors, the latter being hinged to the side girders, as shown in Figs. 3 and 4.

Secured to the upper edge of each of the center sills 3 is a tubular butt or knuckle 10, consisting of a sheet-metal plate having the upper edge thereof above the sill 3 rolled into semicylindrical form, as shown, to form the pivot or knuckle of the hinge. The door 6 is provided at one edge with a plurality of straps 11, which are bent to encircle the tubular butts 10 and which constitute the knuckles of the door, forming part of the hinge-joint. The door 6 also comprises one or more downwardly-extending flanges 12 and an end cross-piece 13 of a reversely-flanged angle-iron, which when the door 6 is disposed horizontally to form a section of the car-floor rests upon the upper ends of flanges 14, projecting from the upper face of the other center door 7, as clearly shown in Fig. 3, the said door 7 being hinged in the same manner as the door 6.

The door 7 is smaller than the door 6 and is provided at its free edge and on its upper side with a flanged stop-cleat 15, which forms a seat or rest for the larger center door 6 when the last-named door is lowered to the position shown in Fig. 4, where the edge of the door 6 is shown as resting on said stop-cleat.

The cross-sills or center separators are provided with horizontal slots 16, in which is arranged a laterally-sliding rod or shaft 17, which forms a support for the door 6, as shown in Figs. 3 and 4. This shaft is moved bodily laterally by means of a plurality of chains 18, which are connected to and wound upon pulleys 19 on a shaft 20, extending longitudinally of the car and journaled in the cross-sills, said shaft being adapted to receive a suitable operating-crank upon its projecting squared end 21. Upon the projecting end of the shaft 20 is a ratchet-wheel 22, adapted to be engaged and held by a dog 23, having an operating-handle 24 connected therewith. The shaft 20 is further provided with one or more cams 25, which operate against the lower side of the door 7 as the door 6 is drawn toward the door 7, said cams serving to thrust the stop-cleat 15 beneath the free edge of the door 6 in the manner illustrated in Fig. 4. This serves to position the center doors in readiness for dumping the load centrally through the bottom of the car.

The side doors 8 are hinged to the tubular butts or knuckles 10 in the same manner as the center doors 6 and 7 and are stiffened at their outer ends by the reversely-flanged

angle-irons 26, while they are provided on their bottoms with one or more downwardly-extending flanges 27, adapted to rest directly upon rolling and traveling shafts 28. 5 Two of these shafts are employed extending lengthwise of the car-bottom at opposite sides, and said shafts are movable lengthwise of guide-slots 29, formed in the cross-sills, as shown. The major portion of each slot 10 is inclined, as shown, while the upper end thereof is extended for a short distance horizontally, as shown at 30, so that when the shaft 28 is in the horizontal portion of the slot it forms a firm support for the superimposed door, the flanges 27 of which rest directly on said shaft. By reason of the horizontal disposition of the portion 30 of the slot there is no tendency of the shaft 28 to recede down the inclined portion of the 15 slot.

Each of the shafts 28 is provided with one or more grooved pulleys 31 and has connected thereto a corresponding number of chains 32, which wrap around the pulleys as 20 the shaft is rotated, the opposite ends of the chains being connected to stationary eyes 33 at the side of the car. Each shaft 28 is provided with a squared extremity 34, adapted to receive a suitable operating- 25 crank, and is further provided with a ratchet-wheel 35, adapted to be engaged by a dog 36, having an operating lever-arm 37, said dog being pivotally mounted on a dog-carrier 38, which travels back and forth on a 30 track or guide 39, secured to the outer face of the end plate 40 of the car, as shown in Fig. 1. Each shaft 28 is further provided at suitable points with spur-pinions 41, which engage with short racks 42 under the horizontal portions of the slots 30, secured to the 35 cross-sills, the geared arrangement shown and described serving to keep the shaft in true longitudinal alinement and also insuring the movement of the shaft from the horizontal portion of the guide-slots to the inclined portions 29 thereof when said shaft is 40 rotated by the operating-crank and caused to move in a direction which will effect a lowering or dropping of the side door-sections 8 when the car is used as a side dumper.

Under the arrangement shown in Fig. 4, in which the car is used as a center dumper, the side door-sections 8 are raised at their outer edges, as shown in said Fig. 4, so that the projecting ends thereof fit into grooves or rabbets 43 in the free edges of the upper sections 9 of the side doors, this arrangement being clearly shown in Fig. 4, wherein 45 it will also be seen that the upper side door-sections 9 rest against projecting steps 44, secured to the sides or longitudinal girders of the car.

In adjusting the parts to form a side-dump car the center doors 6 and 7 are ele-

vated, as shown in dotted lines in Fig. 3, so that the free edge of the smaller door 7 will rest in notches 45 in the flanges 12 of the larger door, thereby forming a central longitudinal ridge which will direct the material with which the car is loaded to opposite sides of the car-bottom ready to be dumped when the side door-sections 8 are dropped.

Hitherto the longitudinal girders or sides of the car-body have been composed of upper and lower angle-irons 46 and 47, respectively, and a connecting web or plate 48 of sheet-iron, and the practice has been to make the upper angle-iron or top sill 46 considerably heavier than the lower angle-irons or bottom sill 47. I purpose to make the upper and lower angle-sills 46 and 47 of approximately or exactly the same size and to employ side stakes or vertical braces 49, extending from the upper sill 46 to the lower sill 47, said side stakes being formed out of reversely-flanged angle-irons and all connected at the upper side by a longitudinal stiffener or brace 50, located at the top of the stakes and in line with the upper sill or angle-iron 46 and securely bolted or riveted thereto, as shown at 51. The construction just described imparts much greater strength to the car sides and enables them the more effectively to resist the lateral strain thrown thereon by the load and at the same time effects a material saving in weight and cost of manufacture.

The ends 5 of the car are braced by horizontally-extending reversely-disposed angle-irons 52, having their ends bent and secured to the slide-plates of the car, extending lengthwise of the ends and secured together by bolts or rivets 53, around which are placed spacing sleeves or thimbles 54, which are enclosed by the channel-irons, as shown in Fig. 2. Each end is also provided with an intermediate longitudinal brace 55, secured to the outer side thereof and held by rivets and spacing-sleeves similar to 53 and 54, above referred to.

The floor of the car further comprises the transverse doors or sections 56, which are hinged thereto at 57 and provided at their free edges with angle-irons 58, adapted to rest upon other angle-irons 59, secured to the stationary section of the floor, as shown in Fig. 2. The doors 56 may be swung upward to the dotted-line position shown in the same figure, in which position they each form a support for the lower end of one of the end plates 5, which is provided at its upper edge with an angle-iron 60 and a hinge-rod 61, the ends of which rest on the top of the car sides, while the lower free edge of the end plate is provided with an angle-iron 62, one flange of which is adapted to hook over and engage the upper edge of the plate or floor-section 56, as shown in the dotted-line position in Fig. 2.

The ends of the rod 61 are adapted to slide on top of the sides and are held beneath straps

63, which also serve to limit the sliding movement of the end plate 5, as clearly shown in Fig. 2, so that when the end plate 5 is swung upward to the dotted-line position of Fig. 2 5 the angle-iron 62 will rest on top of the floor-section 56 when standing vertically.

Instead of extending the sides downward outside of the ends of the cross-sills, as shown in Fig. 3, the cross-sills may extend outward 10 beneath the sides, as shown in Figs. 6 and 7, so that the side sills may rest directly on the cross-sills, in which case metal ties or angle-irons 64 are riveted to the sides and cross-sills, as shown in Figs. 6 and 7, in order to 15 securely anchor said parts together. It will be noted that the flange 65 of the tie 64 is cut away from the top of the cross-sill 1 downward, thus enabling one flange to be riveted to the side and the other flange to be riveted to the cross-sill, all of which is clearly shown in Fig. 6.

From the foregoing description it will be seen that the car may be readily converted into any one of three types—a flat or gondola 25 car, a center-dump car, or a side-dump car—also that means are provided for securely holding the movable parts of the floor-sections or doors in their respective position for adapting the car to its several uses; furthermore, that effective means are provided 30 for adjusting the several parts and supporting said parts firmly when adjusted.

I claim—

1. In a dump-car, the combination with a 35 hinged door or floor section provided with depending flanges of a laterally-movable supporting rod or shaft upon which the flanges of said door or section rest at all times, chains each having one end fastened to said 40 shaft and the opposite end connected to a stationary part of the car at a point distant therefrom, and means for winding said chains so as to cause said rod or shaft to move laterally and operate upon the door or floor section.

2. In a dump-car, the combination with a 50 hinged door or floor section provided with depending flanges of a rolling and traveling shaft upon which the flanges of said door is supported at all times, chains fastened at one 55 end to and adapted to be wound upon said shaft and having their opposite ends connected to a stationary part of the car at a point distant from said shaft, and means for rotating said shaft and causing it to travel laterally while engaging the door or floor section supported thereon.

3. In a dump-car, the combination with a 60 hinged door or floor-section provided with depending flanges of cross-sills provided with inclined guide-slots, a rolling and traveling shaft movable along said guide-slots and forming a support for the flanges of said door or floor-section at all times, chains fastened 65 at one end to said rolling shaft and at the

other end to a stationary part of the car, and means for imparting rotary motion to said shaft.

4. In a dump-car, the combination with a hinged door or floor-section provided with 70 depending flanges and cross-sills provided with inclined slots, of a rolling and traveling shaft movable along said guide-slots and upon which the flanges of the floor-section rest at all times, one or more chains fastened at one end to said shaft and at the other end to a stationary part of the car, means for imparting rotary motion to said shaft, and rack-and-pinion gearing associated with said shaft and cross-sills.

5. In a dump-car, the combination with a hinged door or floor-section provided with 75 depending flanges and cross-sills provided with inclined guide-slots having horizontal end extensions, of a rolling and traveling 80 shaft upon which the flanges of said floor-section rest at all times, said shaft being movable lengthwise of said slots and provided with toothed pinions, one or more chains fastened at one end to said shaft and fastened 85 at their opposite end to a stationary part of the car, stationary racks with which said pinions mesh, and means for rotating said shaft.

6. In a dump-car, a hinged door or floor-section provided with depending flanges in 90 combination with cross-sills provided with inclined guide-slots, a rolling and traveling shaft movable lengthwise of said slots and forming a support upon which the flanges of 95 said floor-section rest at all times, means for rotating said shaft and causing it to traverse the slots, a ratchet-wheel on said shaft, a dog engaging said ratchet-wheel, a dog-carrier embracing said shaft and movable therewith, and a guide or track along which the dog-carrier moves extending parallel with the 100 guide-slot.

7. In a dump-car, the combination with 105 hinged doors or floor-sections, of a laterally-movable rod or shaft for swinging one of said doors, a shaft parallel thereto and mounted in fixed bearings, means for rotating said shaft, one or more chains having their opposite ends connected fixedly to said shafts, and a cam on the rotatable shaft co-operating with the remaining center door, substantially as 110 and for the purpose set forth.

8. In a dump-car, hinged doors or floor-sections, one of which is provided at its free 115 end with a projection and the other with a stop-cleat, in combination with a laterally-movable rod or shaft operating behind one of said doors, a rotary shaft operating in rear of the other door and provided with a cam co-operating directly with the last-named door, means for rotating said shaft, and one or more chains connected at opposite ends to 120 said shafts whereby one rod or shaft is advanced laterally to raise its door, while the 125

- cam of the other shaft acts to advance its door and effect an engagement between the projection of one door and the stop-cleat of the other door, substantially as described.
- 5 9. In a dump-car, the combination with a hinged floor-section adapted to swing from a horizontal to a vertical position, of an end plate hinged and slid able at its upper edge and provided at its lower free edge with an angle-iron, said end plate being adapted to swing from a vertical to an inclined position and to rest upon the floor-section when the latter is disposed vertically.
10. In a metallic car, a car side or side girder embodying top and bottom angle-irons or sills, a connecting plate or web united thereto, stakes or vertical braces extending between said angle-irons or sills, and a longitudinal stiffener or brace extending along the outside of said stakes and firmly secured to the outer flanges of the stakes at a distance from the connecting plate or web, substantially as described.
11. In a dump-car, the combination with the side plates of the car-body, and an inwardly-displaceable end plate, of connecting tie-braces extending across the ends of the car and consisting of reversely-disposed angle-irons, the ends of which are fastened to the side plates, fasteners passing through said angle-irons, and spacing sleeves or thimbles disposed around the fasteners within the channel-irons and between the flanges thereof, substantially as described.
12. In a metallic car-body, the combination with a center sill having a rolled upper edge, of a hinged floor-section having knuckle-straps which encircle said rolled upper edge of the center sill and have their ends secured to the floor-section, an angle-iron cross-piece secured to the free edge of one section, and flanges on the upper side of the other section forming supporting rests or shoulders on which said cross-piece rests when in a horizontal position.
13. In a dump-car, the combination with hinged floor-sections, of a laterally-movable rod or shaft adapted to swing one of the doors, a shaft parallel thereto and mounted in fixed bearings, means for rotating said shaft, one or more flexible connections having their opposite ends connected fixedly to said shafts, and means on the rotatable shaft coöperating with the remaining door, substantially as and for the purpose set forth.
14. In a dump-car, the combination with a hinged floor-section adapted to swing from a horizontal to a vertical position, of an end plate hinged and slid able at its upper edge and adapted to swing from a vertical to an inclined position and to rest upon the floor-section when the latter is disposed vertically.

In testimony whereof I affix my signature in presence of two witnesses.

VICTOR M. SUMMA.
